Atty's.

UNITED STATES PATENT OFFICE.

HARRY W. KULP AND MARTIN C. DELLINGER, OF LANCASTER, PENNSYLVANIA.

VALVE-SPRING COMPRESSOR.

Application filed February 26, 1925, Serial No. 11,771. Renewed October 10, 1928.

The present invention relates to valve-spring lifters particularly intended for use in connection with the internal combustion engines of automobiles.

5 In connection with the grinding of the valves of such engines it is usual practice in most instances to simply lift the valve spring with a suitable tool, for instance such as shown in the patent to Kulp & Dellinger, No. 1,461,-
 10 275, granted July 10, 1923, such lifting being but temporary and to a sufficient distance to allow the pin to be withdrawn, when the tool is withdrawn and the spring left in place about the valve stem, but disconnected there-
 15 from, so that the valve stem is free to turn back and forth during the operation of grinding the valve on its seat. The term "lifting" as above used, and as usually used in this art, means really the compressing of the spring,
 20 by bearing against one end portion, to force such end portion lengthwise of the valve stem a sufficient distance to permit the pin to be removed with ease, and does not ordinarily mean a bodily lifting of the spring, nor its
 25 removal.

However, there are some constructions of internal combustion engines now extensively used in automobiles, for instance the Studebaker Light Six, wherein the assemblage of
 30 the valve stems, push rods, springs and retaining means, is such that the spring cannot be left on the valve stem without interfering therewith and preventing its movement in the grinding operation.

35 The object of the present invention is to provide in combination with the exact quick acting, pivoted lever, constant parallel jaw, locking and releasing construction of valve spring lifter shown in the above identified
 40 patent, means for compressing the valve spring between elements of the tool and holding it compressed during removal bodily from, and bodily replacement about, its valve stem, whereby the spring will be confined
 45 between the operative parts and cannot readily slip out of place when compressed.

In the accompanying drawings:

Figure 1 represents a side elevation of a device embodying my invention in one ex-
 50 treme position;

Figure 2, a fragmentary side elevation thereof with the jaws in intermediate position;

Figure 3, a fragmentary top plan view;
 55 and

Figure 4, a front elevation with the parts in the position of Fig. 2.

Referring now in detail to the drawings, the lifter as a whole, except for the additions of the present invention and improvements, is 60 constructed and operates as in the prior patent to Harry W. Kulp, No. 1,330,542, granted February 10, 1920, and is provided with the lock construction shown in the patent to Kulp & Dellinger No. 1,461,275, granted July 10, 65 1923, to both of which reference is hereby made.

The handles A and B are provided on their operative inner portions with a pivoted jaw C and a pivoted fork or bifurcated part D respec- 70 tively, said parts D and C being maintained substantially parallel at all times throughout their relative movement as the handles A and B are moved relatively about their pivotal connection E, as stated in greater detail in the 75 above referred to patents.

Arms 1 extending vertically at right angles from the respective bifurcations or tines of the fork or part D and secured to the outer faces thereof respectively at at least two points 80 by rivets 2 or other suitable means, or by welding or other suitable means such as will guard against any relative movement between the respective arms 1 and its corresponding tine, extend upward outside of, and on each side 85 of, the jaw C and have their upper end portions for an appreciable distance offset toward each other to confine the valve spring between them in a lateral direction, and have their extreme upper end portions ex- 90 tending toward each other at substantially right angles to their bodies or vertical portions as at 3 to provide jaw faces or seats or a seat to engage against the adjacent end of the valve-spring, and said upper end portions of 95 the arms will preferably be rigidly connected together, preferably by being operatively integral with each other, such connection being preferably by continuing the portions 3, with a depending reinforcing flange so as to 100 merge together in one integral element.

In the construction shown the arms 1 and their right angle jaws 3 and connecting means are all integral, being stamped from a single piece of sheet metal. This is the pre- 105 ferred construction, but it is not essential that they should be integral with each other, or that their upper end portions should be rigidly connected together, or that they should be connected at all, though it is ad- 110

visible that they should be as offsetting any tendency of the upper ends or end portions to spread under stress.

In operation, the jaw C will be fitted under the spring retaining washer or plate or lower end of the spring, and the jaws 3 will be engaged over the upper end of the spring, or convolutions of the spring near its upper end, and the handles A and B will be turned about their pivot E to bring their outer ends together, such movement causing the jaw C and the jaws 3 to approach each other, the parts being locked against reverse movement under the influence of the spring by the lock mechanism, all as described in Patent No. 1,461,275. It is obvious that, in view of the construction maintaining substantial parallelism between the jaw C and part D, the jaws 3 will also at all times be maintained in substantial parallelism with the jaw C, inasmuch as their arms 1 extend vertically with relation to the part D and jaw C and the jaws 3 themselves extend in a horizontal plane from their respective arms 1 and at right angles thereto or substantially so.

However, while it is desirable that the jaws C and 3 shall be at all times substantially parallel as pointed out in more detail in Patent 1,330,542, so that the jaws will act with evenness on the spring in a line parallel to the valve stem and will not compress it more on one side than on the other, it is not essential to the present invention, considered in its broader aspects, that a construction to ensure such parallelism at all times should be embodied in the device, the present invention, in its broader aspects being more concerned with the provision of a construction whereby merely by squeezing one hand together on the handles the valve spring may be compressed and held that way by the automatic locking of the tool so that without need for further attention or consideration the spring may be removed with the tool, being held compressed thereby as removed, during the period it is removed if desired, and replaced, being released after it is arranged again about the valve stem and the retaining means have been put back in original condition, simply by the release of the locking means and the release of the handles of the tool.

Only the preferred embodiment has been illustrated, but it is obvious that the invention is capable of embodiment in many other forms and modifications.

Having thus described our invention, what we claim as new and desire to secure by Letters Patent is:

1. In a spring compressor, two levers each lying on opposite sides of a central line, means for pivotally connecting said levers in such manner that their end portions may move toward and away from each other, and automatic releasable means for locking said levers against movement in one direction, in

combination with parts carried by one end of each of said levers and having movement with relation thereto, means for maintaining said parts substantially in parallel relation throughout the range of movement of said levers, and means secured to one of said parts, straddling the other of said parts and extending beyond the latter, and having portions opposed to the latter part and maintained at all times substantially parallel thereto, said latter part and said portions being adapted to engage the respective end portions of a spring and to force them toward each other to compress said spring, said locking means serving to automatically lock and hold said latter part and said portions in such relation against the action of the compressed spring.

2. In a spring compressor, two levers each lying on opposite sides of a central line, means for pivotally connecting said levers in such manner that their end portions may move toward and from the corresponding portions of the other lever, and releasable means for locking said levers against movement in one direction, in combination with parts carried by the same end portions of each of said levers and having movement with relation thereto, means for maintaining said parts substantially in parallel relation throughout the range of movement of said levers, and arms rigidly secured to one of said parts and extending parallel to each other and on either side of the other of said parts and beyond the latter, and having portions opposed to the latter part and maintained at all times substantially parallel thereto, said latter part and said arm portions being adapted to engage the respective end portions of a spring and to force them toward each other to compress said spring, said locking means serving to lock and hold said latter part and said portions in such position against the action of the compressed spring until released, said arms having portions laterally offset toward each other to confine the compressed spring against a possible tendency to slip in a lateral direction.

3. In a spring compressor, two levers pivotally connected together intermediate their lengths, in combination with parts carried by the adjacent end portions of each of said levers, and means secured to one of said parts, straddling the other of said parts and extending beyond the latter, and having portions opposed to the latter part, which, with said portions, is adapted to engage the respective end portions of a spring to be compressed and to be moved toward or away from each other by the movement of the levers.

4. In a spring compressor, two levers pivotally connected together intermediate their lengths, in combination with parts carried by the corresponding end portions of each of said levers, and arms secured to one of

- said parts, straddling the other of said parts and extending beyond the latter, and having inturned portions opposed to the latter part, said latter part and said portions being 5 adapted to engage the respective end portions of a spring and to compress the latter as the levers are moved in the proper direction, said arms having laterally inwardly offset portions for reducing the interval between 10 the opposed faces of said arms to confine the compressed spring against a possible tendency to slip in a lateral direction.
5. In a spring compressor, a pair of levers movable towards and away from each other, 15 in combination with spring washer engaging means carried by one lever, a part carried by the other lever, and arms extending upwardly from said part and adapted in use to lie on opposite sides of a spring to be compressed, 20 said arms carrying inwardly extending parts for engaging convolutions of such spring at opposite sides of the spring, whereby such spring may be held by, and compressed between, said washer engaging means and said 25 parts.
6. A spring compressor including members movable toward and away from each other, and spring washer engaging means carried by one of said members, in combination with 30 arms secured to the other member and
- adapted in use to lie on opposite sides of a spring to be compressed, and parts extending inwardly from the end portions of the arms toward each other for engaging convolutions of the spring at opposite sides thereof, whereby such spring may be held by, and compressed between, said washer engaging means and said inwardly extending parts. 35
7. A spring compressor including members movable toward and away from each other, 40 spring washer engaging means carried by one of said members, and means for locking said members against movement under influence of the compressed spring, in combination with arms secured to the other member and adapted in use to lie on opposite sides of the spring to be compressed, and parts extending inwardly from the end portions of said arms toward each other for engaging convolutions of the spring at opposite sides thereof, whereby such spring may 45 be compressed between, and held by, said washer engaging means and said inwardly extending parts. 50

In testimony whereof, we have signed our 55 names to this specification at Lancaster, Pennsylvania, this 25th day of February, 1925.

HARRY W. KULP.
MARTIN C. DELLINGER.
